CLAMP

Fenwick L. Ellis, Chicago, Ill.

Application February 27, 1933, Serial No. 658,765

1 Claim. (Cl. 144—300)

This invention relates to improvements in a clamp.

One of the main objects of this invention is to provide a clamp which is simple and economical in construction, so that it can be manufactured and placed on the market at a minimum of cost; and which at the same time is strong and durable, so as to be especially adapted for use by toolmakers, machinists, and so forth.

Another object is to provide a strong clamp consisting of only a few members, all of which can be economically made and conveniently assembled, and which can also be readily disassembled, so that any member can be quickly replaced if necessary.

A further object is to provide a clamp which can be conveniently and easily manipulated; and wherein one jaw is tiltable relative to the other, so that they will readily position themselves to fit exactly and instantly upon the surfaces of pieces of work placed therein, whether parallel or not; and wherein the precise fitting on the work is not disturbed by the tightening of the clamp; and the work pieces can be clamped tightly together, no matter how thin the same may be.

A still further object is to provide such a clamp which can be very tightly applied, to suit the various demands, and wherein the clamp is adapted to be fully snugged or tightened by hand for substantially all work, and either nut may be also additionally tightened by the use of a wrench or pliers, and also by a lever bar.

These and various other objects and advantages will become apparent from the following description, taken in connection with the accompanying drawing, in which the invention is shown in its preferred form, it being understood that various other arrangements and forms of construction may be resorted to for carrying out the objects and purposes of this invention.

In the drawing:

Fig. 1 is a longitudinal central section through my improved clamp, showing the jaws slightly tilted and open for use.

Fig. 2 shows the clamp in action, with the jaws fastened on pieces of work.

In the drawing my invention is illustrated in its preferred form of construction which comprises an upper or movable jaw 10 and a lower or fixed jaw 11, the same being preferably in the form of straight metal bars which have

their forward or gripping ends 10' and 11' beveled, in the usual manner.

A front bolt or screw 12 and a rear bolt or screw 13 are mounted in suitable bores or openings 14 and 15 provided in the lower jaw 11, to extend upwardly therefrom, and they preferably have their lower ends flush with the lower face of said jaw providing a smooth and unobstructed bottom to the clamp. The bolts are mounted to be held fixedly in the jaw, but to be removable therefrom, this being preferably accomplished by making the lower parts of the bolts fit closely in said bores, and by providing holes through the lower jaw and through the bolts wherein pins 16 are inserted with a driving fit, so that they are normally held in position therein but are adapted to be driven therefrom when it is desired to remove the bolts.

The upper jaw 10 is provided with flared openings or apertures 18 and 19 through which bolts 12 and 13 extend, said apertures being preferably flared from their middle part outwardly to both ends thereof, as indicated in the drawing. With this arrangement the upper jaw is freely movable on the bolts for placing it in position on the work, and it is also tiltable thereon so that the jaws are free to fit exactly and instantly upon the outer surfaces of the pieces of work placed therein, whether the same be parallel or not.

A pair of nuts or clamping elements are mounted on the pair of bolts, the same being arranged so that they may be operated by hand, under the usual conditions, for tightening the jaws upon the work, and are also arranged and shaped to be actuated by a wrench or pliers, and by a lever bar, whenever greater force and tightening or snugging up of the jaws is required. These nuts are preferably provided in the form of a wing nut 20 which is mounted and operated on bolt 12, above jaw 10; and a nut 21 which is hexagonal or angular on its exterior and is mounted on bolt 13, to be operated between the jaws. Holes 22 are provided in the wings of nut 20, and holes 23 are provided in angular nut 21, so that a suitable rod or bar 24 may be placed in said holes to enable turning either of said nuts 20 or 21 with greater force; and it is apparent that these nuts are also properly arranged to be engaged and operated by means of a wrench as well as by pliers.

A pair of notches 25 are provided at the rear ends in the adjacent faces of jaws 10 and 11, so that nut 21 may be contained therein, whereby the jaws are adapted to be brought into com-

plete and close contact with their adjacent faces, and are thereby adapted to clamp work pieces of very thin material.

With this disclosed form of construction only 5 a few parts or members are required to make my improved clamp, said members being plain and durable, thus effecting utmost simplicity and economy and also great durability, and the parts are separable so as to provide for replacing the 10 same. The upper jaw is freely tiltable relative to the lower jaw so that the jaws will readily assume their proper position on the work pieces, and they will fit exactly and instantly upon the outer surfaces of any work, whether the same 15 are parallel or not. Herein the upper jaw 10 is placed in position on the work, and nut 23 is then easily spun to contact with said jaw and act as the fulcrum therefor, whereupon the wing nut is turned or spun by hand, without losing 20 the precision of contact with the work. The wing nut is heavy enough and the wings are long enough to provide for rapid spinning thereof and for good leverage, and under normal conditions it can be tightened firmly by hand 25 to produce a tight clamping effect; however, this wing nut, as well as the angular nut, are both shaped and adapted for the additional use of a wrench as well as pliers, and furthermore are also arranged for use of a lever bar

to effect extremely tight clamping of the jaws upon the work.

I claim:

A clamp consisting of an upper and a lower jaw having straight inner faces provided at the rear end with corresponding notches, the upper jaw being provided with flared openings, a pair of bolts mounted in the lower jaw to be flush with the bottom thereof, thereby providing a smooth and unobstructed level bottom on the 10 clamp adapting it to be rested thereon on a level surface, elements mounted with a driving fit in said bolts and lower jaw for securing said bolts rigidly but removably in said jaw, a wing 15 nut mounted on the forward bolt upon the upper jaw, and a nut with angular exterior mounted on the other bolt and positioned within said notches intermediate the jaws to facilitate clamping the jaws completely together, thereby enabling operating said nuts normally by hand 20 and also by a wrench, and there being openings provided in both of said nuts to facilitate operating the same with a lever bar, whereby the jaws can be clamped very tightly together and by reason of the flared openings in the upper 25 jaw will readily and exactly fit the outer surfaces of pieces of work whether parallel or not.

FENWICK L. ELLIS.
